UNITED STATES PATENT OFFICE

161,343

BROOM HOLDER OR THE LIKE

Frank E. Kabase, Birmingham, Ala.

Application March 18, 1950, Serial No. 8,620

Term of patent 14 years

(Cl. D9—2)

To all whom it may concern:

Be it known that I, Frank E. Kabase, a citizen of the United States, residing at Birmingham, State of Alabama, have invented a new, original, and ornamental Design for a Broom Holder or the like, of which the following is a specification, reference being had to the accompanying drawing, forming a part thereof.

Fig. 1 is a perspective view of a broom holder or the like, showing my new design;

Fig. 2 is a plan view thereof; and,

Fig. 3 is a side elevational view thereof.

I claim:

The ornamental design for a broom holder or the like, as shown.

FRANK E. KABASE.
